VANITY CASE

Arthur P. Conant, Fort Thomas, Ky., assignor to
The Wadsworth Watch Case Company, Dayton,
Ky., a corporation of Kentucky

Application February 10, 1950, Serial No. 7,853

Term of patent 3½ years

(Cl. D86—10)

To all whom it may concern:

Be it known that I, Arthur P. Conant, a citizen of the United States of America, residing at Fort Thomas, in the county of Campbell and Commonwealth of Kentucky, have invented a new, original, and ornamental Design for a Vanity Case, of which the following is a specification, reference being had to the accompanying drawing, forming a part hereof.

Referring to the figures:

I claim:

The ornamental design for a vanity case, substantially as shown.

ARTHUR P. CONANT.
